UNITED STATES PATENT OFFICE.

MARK CURTIS, OF ST. LOUIS, MISSOURI.

IMPROVEMENT IN HEATING-STOVES.

Specification forming part of Letters Patent No. 158,252, dated December 29, 1874; application filed April 25, 1874.

To all whom it may concern:

Be it known that I, MARK CURTIS, of St. Louis, in the county of St. Louis and State of Missouri, have invented a new and valuable Improvement in Stoves; and I do hereby declare that the following is a full, clear, and exact description of the construction and operation of the same, reference being had to the annexed drawings, making a part of this specification, and to the letters and figures of reference marked thereon.

Figure 1 of the drawing is a representation of a vertical section of my stove, and Fig. 2 is a front view of the same. Fig. 3 is a horizontal sectional view, and Fig. 4 is a sectional detail view. Fig. 5 is a front sectional view, showing the vertical flues.

This invention has relation to heating-stoves; and it consists of a novel arrangement of flues whereby the heated products of combustion will descend behind the fire-chamber to the base of the stove, thence pass forward to the front thereof, thence rise to a horizontal flue, pass to the back of the stove, and escape into the smoke-pipe, whereby a very large heat-radiating surface is obtained in a comparatively small stove.

The following is a description of my improvement:

In the annexed drawings I have represented my improvement applied to an open fire-grate heater. A is a fire-chamber in which is placed a grate, B, which chamber is provided with doors *a a*, which may be provided with mica lights. Below the grate B is the ash-receptacle, which may be also provided with doors *b b*. D designates the hearth, the sides and back of which are hollow, as indicated by the letter *c*, thus forming a flue at the base of the stove for radiating heat from the products of combustion circulating therein. Back of the fire-chamber A is a descending flue, *d*, which communicates below with the flue *c*, and at its upper end with said fire-chamber, as shown in Fig. 1, and between this flue *d* and the

back wall of the fire-chamber is an air-space, G, into which air is admitted from beneath the hearth D. The upper end of the air-space G communicates with a chamber, H, which is at the back of an oven, J, by means of a number of vertical pipes, *g*, between which pipes the flames and products of combustion pass on their way down through the descending flue *d*. The upper end of the chamber H is covered by the same plate which covers the oven-chamber J, and that portion of this plate which covers the chamber H is perforated for allowing the heated air to escape into the room.

After the heated products of combustion have descended to the bottom of the flue *d*, and passed forward through the flue-spaces *c c*, on opposite sides of the hearth, the products are conducted up through vertical flues, L, to a horizontal flue, L', thence through this flue to the smoke-pipe *g'*. In passing through the said flues the products radiate heat into the room, and also receive heat through the wall of the fire-chamber. In practice, an opening, *e*, is made through the back wall of the fire-chamber leading into the back part of the horizontal flue L', which opening will be provided with a damper for giving a direct draft from the fire-chamber to the smoke-pipe, whenever such a draft is found necessary.

What I claim, and desire to secure by Letters Patent, is—

The rear descending flue *d*, the side base-flues *c*, the front rising flues L, and the top or oven flues L', in combination with an open-front stove and an air-heating flue, substantially as set forth.

In testimony that I claim the above, I have hereunto subscribed my name in the presence of two witnesses.

MARK CURTIS.
